UNITED STATES PATENT OFFICE

JOEL J. BURSON, OF MINERAL WELLS, TEXAS

EGG CASE

Application filed July 17, 1928. Serial No. 293,324.

This invention aims to provide an egg case, intended primarily for shipping purposes, and one object of the invention is to provide a device of the class described which can be manufactured cheaply and be folded up into small compass when desired, the structure being light, portable and strong.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:—

Figure 1 shows in top plan, a device constructed in accordance with the invention;

Figure 2 is a section of the structure shown in Figure 1;

Figure 3 is a view wherein the case is shown folded;

Figure 4 is an end elevation;

Figure 5 is a sectional view of one of the latches;

Figure 6 is a sectional view showing the hinged mounting of the lid.

The device forming the subject matter of this application preferably is made of wire throughout, and includes sides 1 and 2. The side 1 has a rectangular extension 3 and the side 2 has a rectangular extension 4. The extensions 3 and 4 are located in diametrically opposite corners of the case, as Figure 1 will show. An end 5 is provided and is hinged at 6 to the extension 4 of the side 2. The end 5 is hinged at 7 to one extremity of the side 1. An end 8 is provided and is hinged at 9 to the extension 3 of the side 1. The end 8 is hinged at 10 to the extremity of the side 2.

The numeral 11 marks a lid. The lid 11 is hinged at 12 to the upper bar of the side 1. The lid carries spring actuated latches

14 which engage with the upper bar of the side 2. A partition 15 is hinged at 16 to one of the uprights of the side 2 and is connected by a latch 17 with one of the uprights of the side 1, the latch 17 being constructed like the latch 14. The bottom is shown at 18 and is hinged at 19 to the lower bar of the side 2, the bottom being connected releasably by one or more latches 20 with the lower longitudinal bar of the side 1. Flexible elements 21, such as chains, extend across the case from the lower longitudinal bar of the side 1 to the lower longitudinal bar of the side 2 and engage the undersurface of the bottom 18 to aid in supporting the bottom and the load that is superposed thereon.

In practical operation, the partition 15 may be unlatched at 17 and folded into parallelism with the side 2. The lid 11 may be unlatched at 14 and folded into parallelism with the side 1, the bottom 18 may be unlatched at 20 and folded, and, then, the entire case may be flattened down into the compact form shown in Figure 3, the sides and the ends of the case being arranged in pairs, in approximate parallelism to each other, and the offsets or extensions at 3 and at 4 giving room for the parts that are folded inside of the collapsed case.

The device is simple in construction but is so made up that it will be strong to withstand hard use either when set up or knocked down.

Having thus described the invention, what is claimed is:—

In a device of the class described, ends and sides hingedly connected, for folding into approximate parallelism, a lid and a bottom hingedly connected with the sides and foldable within the device when the same is collapsed, and flexible elements extending between the lower portions of the sides and engaged beneath the bottom to aid in upholding the bottom.

In testimony that I claim the foregoing as my own, I have hereto affixed my signature.

JOEL J. BURSON.
